UNITED STATES PATENT OFFICE.

ROBERT C. SCHEMML, OF UNION CITY, INDIANA.

FINISHING-WELT.

1,226,600.

Specification of Letters Patent. Patented May 15, 1917.

Application filed February 7, 1917. Serial No. 147,204.

To all whom it may concern:

Be it known that I, ROBERT C. SCHEMML, a citizen of the United States, residing at Union City, in the county of Randolph and State of Indiana, have invented new and useful Improvements in Finishing-Welts, of which the following is a specification.

My present invention pertains to the finishing of leather and analogous work as used on vehicles and in other connections; and it contemplates the provision of a finishing welt constructed and arranged with a view to being readily nailed, stitched or otherwise attached to the article by which it is carried in such manner that subsequently to the nailing, stitching or other attachment, the welt can be made to assume or assumes of itself such a state that the attaching means will be entirely hidden from view and the finished appearance of the work as a whole will be enhanced.

Other objects and advantageous features of the invention will be fully understood from the following description and claims when the same are read in connection with the drawings, accompanying and forming part of this specification, in which:

Figure 1 is a face view or side elevation of my model welt *per se*.
Fig. 2 is an enlarged transverse section of the same, taken in the plane indicated by the line 2-2 of Fig. 1.

Fig. 3 is a detail elevation illustrative of the manner in which the beads or raised portion of various shapes not herein described of the welt are spread apart to facilitate the convenient nailing or other attachment of the welt to the article by which the same is to be carried.

Fig. 4 is an enlarged cross-section showing the welt nailed to a portion of frame work, and also showing the beads or raised portion of the welt separated to permit of the nailing or other means of attaching being readily accomplished.

Figs. 5 and 6 are views of modifications.

Referring by numeral to said drawings and particularly to Figs. 1-4 thereof,

1 is the body or base, possessed of resiliency and on which beads or raised portions are arranged in parallel relation and close together and are connected with the body or base. As shown the body or base 1 is made up of layers of leather or other suitable material though it may be made of a single

thickness if desired. The layers are stitched or otherwise fastened together at 4, while the beads or raised portions are formed by cords or other fillings 3 and cord-coverings 2, the latter being preferably parts of the body 1, as shown. It will be manifest that the beads or raised portions are capable of being spread apart for the convenient placing of any attaching means through the part of the welt adapted to receive the same; also, that when the spreading means is removed the beads or raised portions will have a tendency to spring back to the closely adjacent positions shown in Figs. 1 and 2, and consequently will effectually hide from view the nails, stitches or other attaching means arranged in the base or body 1. This will be appreciated as an important advantage when it is stated that the hiding from view of the attaching means complementary to the welt is calculated to materially enhance the finished appearance of the welt and the work as a whole.

As shown in Figs. 1 and 2, my novel welt is adapted to be either nailed or stitched or otherwise fastened to the article by which it is to be borne. In Figs. 3 and 4, however, the welt is shown as connected by nails 6 which are driven through the layers 5 of the base or body 1. It will also be understood by reference to the right of Fig. 3 that the beads are shown as spread apart. This, however, is only effected by the interposition of a tool or finger between the beads, and when the tool or finger is removed, the beads will spring back into the parallel relation and closely adjacent to or against each other and hence will hide the nails 6 shown at the right of Fig. 3.

In Figs. 5 and 6 I illustrate embodiments of my invention for use where a beading is intended to pass through the center of the welt so as to permit the beads or raised portions or edges of the welt to "clamshell" closely to the inserted portion, thereby bringing about the result of hiding the tacks or other fastening means employed for the welt.

In Fig. 5 the beads or raised portions 2 are spaced apart, and an auxiliary bead 7 is arranged between and held by the bead 2 so as to cover the fastening means 6. Otherwise this construction is similar to that shown in Figs. 1-4.

In Fig. 6 the auxiliary, longitudinal-cen-

tral bead 8 is held by one bead or raised portion 8 and is secured on the other side by the line of stitches 4.

It will be noted that in accordance with 5 my invention the tacks or other means of fastening may be placed at regular or irregular intervals as may be made necessary because of metal obstructions or other hindrances which may be encountered incidental to the attachment of the welt.

I have entered into detailed descriptions 10 of the present embodiments of my invention in order to impart a full, clear and exact understanding of the same. I do not desire, 15 however, to be understood as confining myself to the specific construction shown and described as in the future practice of the invention such changes or modifications may be made as fairly fall within the scope of 20 my appended claims. For instance, leather, metal or other suitable materials may be inserted to answer the two-fold purpose of hiding the means of fastening and enhancing the finished appearance of the welt.

25 Having described my invention, what I claim and desire to secure by Letters Patent, is:

1. As a new article of manufacture, a welt comprising a body, and longitudinal parallel beads superimposed on and connected with the body, the body being constructed and arranged to permit of the beads being spread apart and subsequently resuming their normal close-together positions, for 35 the purpose set forth.

2. As a new article of manufacture, a welt comprising a body made up of layers of material or materials, and longitudinal parallel beads superimposed on and joined to the 40 body, the said beads being formed of cords and coverings extending from layers of the body, and the body being constructed and arranged to permit of the beads being spread apart and subsequently maintained in their 45 normal close-together positions.

3. The combination of an article, a welt arranged against the same and comprising a body, and beads joined to the body and normally resting close together and constructed and arranged to be spread apart, and attaching means extending through the longitudinal central portion of the body and joining the same to the article; the said attaching means being normally hidden from view by the said beads in their closely arranged positions.

4. The combination of an article, a welt arranged against the same and comprising a body, and beads joined to the body and normally resting close together and constructed and arranged to be spread apart, and attaching means extending through the body and joining the same to the article; the said attaching means being normally hidden from view by the said beads in their closely arranged positions.

5. As a new article of manufacture, a welt comprising a body, and longitudinal parallel beads superimposed on and connected with the body and constructed and arranged to have a tendency when moved laterally outward to move inwardly toward each other and remain of themselves in the latter positions.

6. As a new article of manufacture, a welt comprising a body, and longitudinal parallel beads superimposed on the body and made up of fillings and coverings; the said coverings being connected with the body and constructed and arranged to enable the 75 beads when moved laterally outward to move inwardly toward each other and remain of themselves in the latter positions.

In testimony whereof I have hereunto set my hand in presence of two subscribing witnesses.

ROBERT C. SCHEMML.

Witnesses:

ELLA PIEPER,
WM. E. HARRISON.

DISCLAIMER

1,226,600.—*Robert C. Schemmel*, Union City, Ind. FINISHING-WELT. Patent dated May 15, 1917. Disclaimer filed August 15, 1933, by the assignee, *Backstay Welt Company*.

Hereby disclaims claims 3 and 4 of said Letters Patent which are in the following words, to wit:

“3. The combination of an article, a welt arranged against the same and comprising a body, and beads joined to the body and normally resting close together and constructed and arranged to be spread apart, and attaching means extending through the longitudinal central portion of the body and joining the same to the article; the said attaching means being normally hidden from view by the said beads in their closely arranged positions.

“4. The combination of an article, a welt arranged against the same and comprising a body, and beads joined to the body and normally resting close together and constructed and arranged to be spread apart, and attaching means extending through the body and joining the same to the article; the said attaching means being normally hidden from view by the said beads in their closely arranged positions.”
